UNITED STATES PATENT OFFICE.

ALEXANDER M. PASNIK, OF NORWICH, CONNECTICUT.

NAILBRUSH.

Application filed March 7, 1925. Serial No. 13,672.

To all whom it may concern:

Be it known that I, ALEXANDER M. PASNIK, a citizen of the United States, residing at Norwich, in the county of New London and State of Connecticut, have invented new and useful Improvements in Nail-brushes, of which the following is a specification.

The object of this invention is to provide a nail-brush of a simple, inexpensive, and very compact nature, convenient and effective to use, and possessing the further advantage that the brush proper when worn can be discarded and replaced by a fresh brush. The brush comprises two parts, separably connected, and formed and constructed in the manner which will be more particularly pointed out.

In the accompanying drawings, forming part hereof:

Fig. 1 is a perspective view of the assembled device, indicating the manner in which it is held;

Fig. 2 is a cross-section at the middle of Fig. 1;

Fig. 3 is a cross-section of Fig. 1, taken at the region of one of the studs;

Fig. 4 is an elevation of the brush proper; and

Fig. 5 is an elevation of the bar forming the other part of the device.

The brush member 2 has a thin back 3, with a row of bristles 4 set in one edge. Two slots or notches 5 extend in from the opposite edge, near the ends. Both of these slots extend in a generally similar sense, that is to say toward the bristles, with their entrances away from the bristles.

The other part of the device is preferably in the form of a flat guide bar 6, longer than the brush proper, and having its ends

7 notched to form finger and thumb holds, enabling the device to be held between the thumb and a finger of one hand. The brush member is applied flatly to one side 45 face of the bar 6, in such manner that a margin 8 of the said face extends beyond the bristles to form a guide for the fingers the nails of which are being cleaned. The bar has a pair of studs, or headed pins, 9 50 which project from its side face in positions to be engaged by the slots 5, which are formed to grip the pins when the brush is slipped transversely straight rearward into place, for which purpose the slots may be 55 slightly divergent as shown, or otherwise slightly distorted to have a wedging or locking action on the pins. The pressure of the nails against the brush in cleaning is rearward against the studs. 60

The brush member can be instantly applied to and removed from the guide bar, and when worn can be replaced by another. In use, the device can be held in any position desired, and the brush member is firmly 65 supported and held by the studs alone.

What is claimed as new is:

A nail-brush comprising a guide-bar having spaced headed studs projecting from one face thereof, a brush member comprising a thin back having bristles mounted on one edge thereof, said back being provided with a plurality of slots having their entrances for the studs disposed oppositely from the bristles, said back being arranged 70 flat against said guide-bar with the bristles terminating adjacent the edge of the guide-bar and with the lugs frictionally engaged in said slots for detachably retaining the brush member in operative relation to the 75 guide-bar. 80

ALEXANDER M. PASNIK.
